CORE BIT

Charles A. Dean, Compton, Calif.

Application March 15, 1937, Serial No. 131,090

7 Claims. (Cl. 255—72)

This invention pertains to improvements in earth-boring core drills, and particularly to means for controlling flow of drilling fluid in passages of the drill head.

5 Core drills operate in muddy fluid at the bottom of the drill hole. Such fluid is pumped down from the surface through the drill barrel and flows through orifices near the cutters. This tends to clog the various passages. For example, the mud 10 at high temperatures, such as are encountered in some of the deep wells, tends to become exceedingly viscous and even to bake. Moreover, plugging commonly occurs when a drill is lowered into the mud at the bottom. The muddy fluid flows 15 from without the drill seeking its own level in the empty drill passages, to a height determined by the prevailing hydraulic pressure. Ordinarily this mud contains suspended solids of a size sufficiently large to clog the drill orifices or the passages surrounding the inner core barrel. These 20 solids become so firmly wedged under pressure of the fluid flowing into the drill that frequently despite counter-pressure when the mud pumps are started, some of the passages remain clogged 25 during drilling.

An object of this invention is to provide improved means for avoiding plugging of the fluid passages of a core drill and to assure uniform operation of the various orifices during drilling. A 30 particular object is to provide a core drill adapted to keep the space between an inner core barrel and the outer drill barrel free from plugging when the drill is lowered into mud at the bottom of a drill hole. A further object is to divert drilling fluid from the annular space about an inner core barrel until predetermined pressures are 35 available for flushing the annular space and its outlet orifices. Yet another object is directed to core drills of the type having a vertically reciprocal inner core barrel to actuate core-gripping dogs, such for example as the drills shown in U. S. Patents No. 1,850,386 or 1,984,867. Such objects are to provide means in such drills for positively diverting drilling fluid from outside the inner core 40 barrel regardless of the position of the barrel when the drill is in mud at the bottom. These and other objects will be apparent in the following description of a specific illustrative embodiment of the principles of this invention.

50 Reference is made to the accompanying drawing of a preferred form of this invention and to the appended claims which particularly point out novel features of this invention.

In broad principle, these and other objects are 55 accomplished advantageously by providing a drill

in which are an inner core barrel and a fluid passage outside the core barrel, a valve co-operating therewith for closure of the passage, and a releasable latch to control the valve. In more specific and preferred form the valve is held by a shearable pin to close the passage. This valve contains a relatively large fluid conduit communicating between drill stem and the interior of the core barrel to maintain low pressure on the latch, and contains a seat for closure of the port so that 10 pressure may be applied to move the valve to open the passage outside the core barrel.

In the drawing:

Fig. 1 is a cross-sectional view of a core drill with inner core barrel and fluid-diverting valve 15 in non-drilling position, and

Fig. 2 is a cross-sectional view similar to Fig. 1 but with the inner barrel closed and valve open to divert fluid for drilling.

Referring more particularly to the drawing, a 20 core drill 1 is shown containing an inner core barrel 2 in the drill head. In the form shown, though other forms may be used, this barrel is of the vertically reciprocal type which actuates core gripping dogs. Core barrel 2 is surrounded by 25 annular passage 3 which communicates at the bottom through jets 4 with the drilling cutters 5. Passage 3 at the top communicates with a central bore 6 in the drill stem through intermediate ports 7 in the upper end of the core barrel 2. Pas- 30 sage 3 above ports 7 is closed by resilient rings 8 about the upper end of core barrel 2.

Within the upper end of core barrel 2 a valve sleeve 9 is fitted to slide vertically past the ports 7 so as to close ports 7 when the valve is in upper 35 position and to open the ports when in lower position. The valve sleeve is open throughout and fitted snugly to slide between constricted walls of the core barrel. Limits for vertical movement of the valve sleeve are established by shoulders 10 40 and 11 on the sleeve to engage corresponding stops in the walls of the core barrel.

Through the constricted wall of the core barrel and the contacting side portion of the valve sleeve are horizontal openings 12 and 12a to register 45 with each other when the valve sleeve 9 is in upper position. Thus a pin 13 to serve as a releasable latch may be inserted therein to lock valve 9 in position to cover ports 7 and prevent diversion of fluid between annular passage 3 and drill bore 6. 50 Pin 13 is inserted before a drill is lowered into a drill hole. This pin may consist of a nail or the like, of size commensurate to shear under the contemplated pressures when the valve 9 is closed.

Valve sleeve 9 contains an elongate fluid pas- 55

sage 14. This passageway 14 at its top is provided with a flaring valve seat 15 to receive a ball 16 to close conduit 14, against communication of fluid between the space within core barrel 2 and bore 6 of the drill stem.

In operation, as a drill is being lowered to the bottom of a drill hole, drilling mud and debris under hydraulic pressure flow into the drill and rise to seek the level of the fluid outside. This fluid contains particles large enough to jam in the passage surrounding the inner core barrel or else to jam in the jets opening near the cutters. Under the prevailing hydraulic pressure such stoppage of these passages usually occurs in ordinary drills. Moreover under modern conditions of core drilling at great depths in the earth the adverse factor of high temperature tends to bake or gel the mud that rises through the cutter jets. Consequently with ordinary drills when the pressure is reversed for drilling and even though pump pressure is applied, the drill fluid flows out unevenly and the action and wear of the cutters is irregular.

However, when a drill embodying the present invention is lowered into a bore hole, annular passage 3 is closed at the upper ports 7, and the hydraulic pressure on the mud at the bottom of the drill is relieved through the opening 14 in the top of the core barrel. The relatively large cross-section of the core barrel facilitates flow of the mud therein even though solid particles of considerable size be present. But flow in the annular passage 3 is substantially avoided, for with outlet at ports 7 closed, back pressure of the entrapped air and the relative constriction of passage 3 divert the mud unto core barrel 2. Air in core barrel 2 escapes freely through passage 14.

When this improved drill reaches bottom and is ready for drilling, pumps are started in customary manner to force drilling fluid down through the drill stem. At first the fluid may flow out through core barrel 2. Then ball closure 15 is dropped with the fluid through the stem and seats itself in valve sleeve 9, closing opening 14. Thus pressure of the pumps and drilling mud is exerted on valve 9 so that finally the sleeve is forced down to release the latch, or shear the latch pin 13, as shown in Fig. 2. Thus ports 7 are opened so that with the predominant pressure downward and with annular passage 3 clear, drilling mud from the pumps readily flows uniformly through the cutter orifices for drilling.

While in accordance with the patent statutes a particular embodiment of this invention has been described for illustration of the principles thereof, and the best mode of application now contemplated, it is evident that variations and other specific arrangements are contemplated and various adaptations of this invention may be made by those skilled in this art, within the scope of the appended claims.

What is claimed is:

1. A core drill comprising a bit head adapted to be attached to a hollow drill stem, a core barrel therein and a fluid passage around the core barrel, either the core barrel or the fluid passage being open for flow of fluid between the drill stem and the bottom cutters of the bit, means initially to close the fluid passage and to divert fluid through the core barrel, and means to close the core barrel and to divert fluid through the fluid passage to the cutters.

2. A core drill comprising a bit head adapted to be attached to a hollow drill stem, a core barrel vertically movable therein and initially open

at the top for flow of drilling fluid therethrough, and a fluid passage outside the core barrel communicating between the drill stem and the bottom cutters of the drill, said passage initially being closed at its top, and valve means to close the core barrel at any vertical position and to open the passage for diverting flow of fluid to the bottom cutters for drilling.

3. A core drill comprising a bit head adapted to be attached to a hollow drill stem and containing a core barrel and a fluid passage outside the core barrel communicating between the drill stem and the bottom cutters of the drill, closure means for the passage around the upper portion of the core barrel, ports in the core barrel initially affording fluid communication between the portions of the passage above and below the closure, a valve to close said ports and means to open said valve and ports for fluid to flow to the cutters through the passage outside the core barrel.

4. An earth drill comprising a head adapted for attachment to a hollow drill stem, a core barrel therein, a fluid passage outside the core barrel open at the bottom and closed near the top of the core barrel, ports in the upper part of the barrel to open between the passage and the drill stem, a valve at the upper part of the core barrel to close the ports, said valve containing a fluid conduit communicating between the drill stem and the interior of the core barrel, and a seat in said valve to receive a closure element for the conduit, said valve being adapted to move relatively to the core barrel to open the ports when the closure element is seated in the valve.

5. A core drill comprising a bit head adapted to be attached to a hollow drill stem, a core barrel therein open at the top, a fluid passage outside the core barrel and closed near the top of the core barrel, ports between the passage and the core barrel opening, a sleeve fitting in the core barrel opening and movable to open or to close the ports, and means to close the sleeve and core barrel opening and move the sleeve to open the ports and divert fluid through the passage outside the core barrel.

6. A core drill comprising a bit head adapted to be attached to a hollow drill stem, a core barrel open at the top and mounted in the bit head to move longitudinally thereof, a fluid passage outside the core barrel and closed near the top of the core barrel, ports between the passage and the core barrel opening, a sleeve fitting in the core barrel opening adapted to afford fluid communication between the drill stem and the core barrel and adapted to move to open or to close the ports, and a seat to receive a closure element for the sleeve, whereby under fluid pressure the closed sleeve is adapted to move to open the ports and divert fluid through the passage outside the barrel.

7. A core drill comprising a bit head adapted to be attached to a hollow drill stem, a core barrel open at the top, a fluid passage outside the core barrel, and closed near the top of the core barrel, ports between the passage and the core barrel opening, a sleeve fitting in the core barrel opening and movable to open or to close the ports, and means holding the sleeve to close the ports when the sleeve is open and releasable on closing the sleeve, and means to close the sleeve and core barrel opening and move the sleeve to open the ports and divert fluid through the passage outside the core barrel.
